UNITED STATES PATENT OFFICE.

GEORGE W. WILSON, OF ROCKCREEK, IDAHO, ASSIGNOR OF ONE-HALF
TO JAMES E. McEVOY, OF HAGERMAN, IDAHO.

WHIFFLETREE-HOOK.

No. 812,390.

Specification of Letters Patent.

Patented Feb. 13, 1906.

Application filed May 23, 1905. Serial No. 261,769.

To all whom it may concern:

Be it known that I, GEORGE W. WILSON, a citizen of the United States, residing at Rockcreek, in the county of Cassia and State of Idaho, have invented a new and useful Whiffletree-Hook, of which the following is a specification.

The invention relates to improvements in whiffletree-hooks.

10 The object of the present invention is to improve the construction of whiffletree-hooks and to provide a simple and comparatively inexpensive device which will effectually prevent a trace from becoming accidentally unfastened and which will be adapted to receive a harness having either a flat trace or a chain, whereby much time will be saved when changing a horse or team from a heavy to a light vehicle, or vice versa.

15 A further object of the invention is to dispense with springs in the construction of whiffletree-hooks and to provide trace-holding means adapted to be readily operated to secure a trace to or release the same from a 20 whiffletree and capable in event of breakage of being readily replaced at a small cost.

With these and other objects in view the invention consists in the construction and novel combination and arrangement of parts 25 hereinafter fully described, illustrated in the accompanying drawings, and pointed out in the claims hereto appended, it being understood that various changes in the form, proportion, size, and minor details of construction 30 within the scope of the claims may be resorted to without departing from the spirit or sacrificing any of the advantages of the invention.

In the drawings, Figure 1 is a perspective 35 view of a whiffletree-hook constructed in accordance with this invention, the trace-holder being closed. Fig. 2 is a similar view, the trace-holder being open. Fig. 3 is a transverse sectional view, the parts being arranged as shown in Fig. 1.

Like numerals of reference designate corresponding parts in all the figures of the drawings.

1 designates a sleeve or ferrule closed at 40 its outer end and forming a cap for the ends of a whiffletree 2 and provided at its front with an integral trace-receiving hook 3 and having a trace-receiving tongue 4 extending

from its outer closed end. The hook 3 and the tongue 4 are preferably formed integral 55 with the sleeve or ferrule; but they may be of any other desired construction, as will be readily understood. The trace-receiving hook 3 is connected at its inner side to the sleeve or ferrule and its outer side 5, which constitutes the bill, is spaced from the sleeve or ferrule, as clearly shown in Fig. 3, to enable a ring or link of a trace-chain to be readily engaged with it. The tongue or stud 4, which is provided at its outer end with a horizontally-disposed head, is adapted to extend through the eye of a leather trace, and by providing both a hook and a tongue or stud 60 the whiffletree is adapted to be connected with any kind of harness, thereby obviating 65 the necessity of changing the harness of a horse when it is changed from one kind of a vehicle to another. A trace is retained in engagement with the whiffletree by means of a pivoted or hinged trace-holder 6, which is 70 adapted to be swung upward from the position shown in Fig. 1 to that illustrated in Fig. 2 and which has a transversely-curved body portion conforming to the configuration of the whiffletree. The body portion of the 75 trace-holder is provided at its inner end with a pair of ears 7, which are curved to fit the whiffletree and which are perforated to receive a transverse pin or pivot 8, which forms a pintle for the trace-holder. The ears 7 are 80 arranged at an inclination and extend downwardly and inwardly toward the inner end of the sleeve or ferrule when the trace-holder is closed.

The trace-holder is provided at its outer end 85 with a pair of transversely-disposed clamping-jaws 9, which are curved downwardly and which are adapted to embrace the whiffletree at a point below the horizontal diameter thereof, whereby the trace-holder is 90 effectually prevented from being swung upward accidentally. The terminal 10 of the depending clamping-jaws are bent outwardly, being arranged in substantially a horizontal plane, as clearly shown in Fig. 3 of the drawings. These outturned terminals serve as 95 convenient means for disengaging the clamping-jaws from the whiffletree to permit the trace-holder to be swung upward. Also the outturned end of the front jaw is interposed 100 between the bill of the hook and the whiffle- 105

tree and is adapted to close the entrance to the hook 3 for confining a link or ring of a trace in engagement with the hook.

The trace-holder is provided at its outer end with a hook 11, consisting of an angularly-disposed arm 12 and a depending bill or engaging portion 13, which extends through an opening 14 of the trace-receiving tongue of the whiffletree when the trace-holder is closed.

When the trace-holder is closed, as illustrated in Fig. 1 of the drawings, the space between the bill of the hook 3 and the whiffletree is closed and the engaging end portion or bill 13 of the trace-holder extends through the opening 14 of the tongue or stud, so that a trace will be securely fastened to the whiffletree whether in engagement with the hook 3 or the tongue or stud 4. The trace-holder will not become frozen or inoperative in cold weather, and should it become broken it can be readily replaced at a very small cost. The hook 11, which engages the projecting tongue of the whiffletree, is also adapted to be readily grasped for enabling the trace-holder to be swung upward to release the trace.

Having thus fully described my invention, what I claim as new, and desire to secure by Letters Patent, is—

30 1. In a device of the class described, the combination of a whiffletree, a trace-receiving hook arranged at the side thereof, a trace-receiving tongue located at the end of the whiffletree, and a movable trace-holder provided with means for engaging the tongue and for simultaneously closing the entrance to the hook.

2. In a device of the class described, the combination of a whiffletree, a trace-receiving hook arranged at the side thereof, a trace-receiving tongue located at the end of the whiffletree, and a pivoted trace-holder arranged to swing upward and downward to open and close it and provided with means for confining a trace in engagement with the tongue or the hook.

3. In a device of the class described, the combination of a whiffletree, a trace-receiving hook arranged at the side thereof, a trace-receiving tongue located at the end of the whiffletree, and a pivoted trace-holder arranged to swing upward and downward to open and close it and provided with means for confining a trace in engagement with the tongue or the hook, said trace-holder being also provided with clamping means for holding it in its closed position.

4. In a device of the class described, the combination of a whiffletree provided at the side with a hook and having a tongue at the end, and a pivoted trace-holder arranged to open and close and provided with means for confining the trace in engagement with the

hook or tongue, said trace-holder being also provided with a pair of clamping-jaws located 65 at opposite sides of the whiffletree for retaining the trace-holder in its closed position.

5. In a device of the class described, the combination of a whiffletree provided at the side with a hook and having a tongue at the 70 end, and a pivoted trace-holder provided with means for engaging the tongue for retaining the trace thereon, said trace-holder being also provided with a pair of clamping-jaws located at opposite sides of the whiffletree, the jaw adjacent to the hook being extended at the bill of the same to close the entrance to the hook.

6. In a device of the class described, the combination of a whiffletree provided with a 80 side hook and having an end tongue, and a pivoted trace-holder provided with opposite clamping-jaws and having an extended end portion arranged to engage the tongue.

7. In a device of the class described, the 85 combination of a whiffletree provided with an end tongue, and a pivoted trace-holder provided at opposite sides of the whiffletree with clamping-jaws and having a hook at its end for engaging the tongue.

8. In a device of the class described, the combination of a whiffletree provided with a tongue, and a pivoted trace-holder having laterally-extending clamping-jaws and provided with a hook consisting of an inner arm 95 or shank and a narrow depending bill arranged to extend through the tongue.

9. In a device of the class described, the combination of a whiffletree provided with a hook having its bill arranged in spaced relation with the whiffletree, a pivoted trace-holder provided at opposite sides of the whiffletree with clamping-jaws for retaining the trace-holder in its closed position, the clamping-jaw adjacent to the hook being provided 105 with an extension located in the space between the bill of the hook and the whiffletree.

10. In a device of the class described, the combination of a whiffletree having a side 110 hook and provided at the end with a tongue, and a trace-holder comprising a body portion provided at its inner end with ears pivoted to the whiffletree, clamping-jaws extending laterally from the outer end of the trace-holder, and a hook located between the clamping-jaws and extending from the outer end of the body portion of the trace-holder.

In testimony that I claim the foregoing as my own I have hereto affixed my signature 120 in the presence of two witnesses.

GEORGE W. WILSON.
